DETACHABLE ELECTRICAL CONNECTOR

Oscar S. Field, Rochester, N. Y., assignor to General Railway Signal Company, Rochester, N. Y.

Application December 27, 1935, Serial No. 56,351

3 Claims. (Cl. 173—328)

This invention relates in general to electrical apparatus, and more particularly to a detachable connector permitting electrical conductors to be conveniently connected to or removed from electrical apparatus of the type such as employed in railway signalling systems or the like.

The relays and the like of a railway signalling system form a part of a rather complicated organization of electrical circuits upon which the 10 operation and safety of trains depends, and consequently it is very important that the external electrical connections to these relays be always properly connected thereto and so connected that a reliable low resistance electrical connection is 15 formed. However, it is necessary to occasionally remove the relays from the system for replacement, repair or the like, and consequently the large number of circuits involved in making such a change often results in delaying normal operation of the signalling system for an undue length 20 of time, and also there is a great possibility of improperly replacing the electrical connections with possible danger of improper operation or of further delay.

25 In view of the above and other considerations, it is proposed in accordance with the present invention, to provide a plug connecting means whereby electrical connections may be, as a unit, conveniently connected to or disconnected, an 30 electrical device of such a signalling system without the possibility of improperly replacing such electrical conductors and with a minimum delay to the proper operation of the system. More 35 specifically, it is proposed to provide an improved plug coupling means attached to an electrical device such as a relay with insulated plug members 40 permanently connected to the elements of the relay and a cooperating detachable member having means permanently connected to the external 45 circuits and arranged to provide a reliable low resistance connection with the plug members. It is further proposed to provide such a plug coupling means which can be connected only in a manner which properly connects the 50 external circuits to the electrical device, and to provide a simple and reliable means for retaining the separable members in their coupled positions.

55 Other objects, purposes and characteristic features of the present invention will appear as the description thereof progresses, during which references will be made to the accompanying drawing, in which:

Fig. 1 is a front elevational view of a plug connecting means constructed in accordance with

the present invention and illustrated with certain parts broken away.

Fig. 2 is a plan view of the plug connecting means shown in Fig. 1 also having certain parts broken away. The plug connecting means in Fig. 2 is illustrated in its disconnected position and with one member illustrated as attached to a relay shown by dot and dash lines.

Fig. 3 is a perspective view illustrating certain details of the present plug coupling means.

In the accompanying drawing, a plug coupling means is shown in a form arranged to connect 14 separate electrical conductors, and as illustrated in Fig. 2, the plug or male member is illustrated as mounted above a relay of the type shown, for example, in Patent No. 1,824,129 granted September 22, 1931 to O. S. Field, but it is understood that the present plug coupling means could be employed to connect any other group of electrical circuits and need not necessarily be mounted upon a particular piece of apparatus. The portion of the relay illustrated in Fig. 2 by dot and dash lines comprises two operating coils 4 mounted above a top insulating panel 5, which panel 5 carries the relay terminals, a few of which terminals have been illustrated by binding posts 6. The binding posts 6 are of course connected to the armature operated contacts, fixed contacts and operating coils of the relay in the usual manner.

The male portion of the present plug coupling means comprises a panel 8 of suitable insulating material such as a molded phenolic compound, which panel 8 carries a plurality of spaced extending prong members 9. These prongs 9 have a rectangular shaped cross section and extend through closely fitting slots in the panel 8 with angular brackets 10 soldered or welded near the inner ends thereof (see Fig. 3) to form a shoulder which rests in depressions in the inside surface of panel 8. A retaining plate 12 of insulating material having slots receiving the inner ends of prongs 9 is provided to engage the shoulders formed by brackets 10 of the prongs 9 and thus retain the prongs in their illustrated position within the panel 8.

A cover member 14 also of insulating material such as a molded phenolic compound encloses the inner ends of prongs 9, the edges of the cover member 14 fitting into an angular groove in the panel 8 and a ledge (not shown) on the sides of the cover 14 engage the inside surfaces of the retaining plate 12 thus holding the plate 12 against the panel 8. The cover 14 is detachably retained in place by two screws 15 extending 55

therethrough and threaded into inserts 16 molded into the panel 8. Insulating spacing bushings 17 are provided around the body portion of screws 15 between the retaining plate 12 and the cover 14, the cover 14 having cup shaped bosses receiving the ends of these bushings 17.

The plug member thus assembled may be mounted on the electrical apparatus such as the illustrated relay by a suitable mounting bracket 10 the upper end being clamped thereto beneath the heads of screws 15 while the lower end may be carried beneath the heads of bolts 21 employed to assemble the magnetic structure of the relay. Suitable insulated electrical conductors 23 are soldered to the inner ends of prongs 9 as shown, which conductors 23 extend to the center of cover 14 and are formed into a cable 24 extending through an opening in the rear of cover 14. A grommet 25 of rubber or other pliable insulating material is provided in the outlet in the cover 14 to protect the cable and to fill the void between the cover 14 and cable 24.

In order to install the various conductors 23 upon the prongs 9, it will of course be clear that the cover 14 is removed from the panel 8 by removing screws 15 thereby permitting the conductors 23 extending through the grommet 25 to be conveniently soldered to the ends of prongs 9 as shown, whereupon the cover is replaced 30 to form a complete enclosure protecting these connections from dust and dirt and from contacting with other objects or from physical damage. The conductors 23 when grouped into a cable may be bound or covered with a suitable woven fabric 35 material as shown and extending downwardly at the rear of the relay wherat these conductors 23 may be separated and attached to their respective relay binding posts 6.

The detachable or female portion of the present 40 plug coupling means is organized in a very similar manner to the stationary or male portion just described. A panel 28 of similar material and dimensions to panel 8 is provided having enlarged rectangular slots therein spaced according to the spacing of the prongs 9, which slots receive the sockets arranged as clearly shown in Fig. 3. These sockets are each formed of a metal strip 29 of a general U-shape with a rearwardly extending lug formed by a loop of the same material. This U-shaped piece 29 surrounds a contacting strip 30 formed of a single piece of spring material such as phosphor-bronze, which contacting strip 30 substantially forms a liner for the U-shaped piece 29 except that the center portions are bowed inwardly so that the minimum distance between this bowed portion is less than the thickness of the prongs 9, and this bowed portion is provided with a longitudinal pressed out portion forming contacting surfaces which are 50 to engage opposite sides of the prongs 9. The U-shaped piece 29 and contact strip 30 are assembled as shown to form a socket by a hollow rivet 31 inserted through the rearwardly extending lug.

The outer end of each of the slots in the panel 28 which receive these U-shaped pieces 29 is of a reduced dimension which readily receives a prong 9 but which forms a shoulder engaged by the ends of the U-shaped piece 29 when inserted therein as may be seen in Fig. 2. A retaining plate 32 similar to plate 12 of the male member is provided with rectangular holes receiving the lugs of the U-shaped pieces 29 and engaging the shoulders of these pieces 29 whereby the sockets are retained within the rectangular

slots of panel 28. The same cover member 14 may be employed on the female portion as employed on the male portion, and this cover may be retained by screws 15 threaded into inserts 16 with spacers 17 also in the same manner.

Electrical conductors 33 corresponding to each of the electrical conductors 23 are soldered to the lugs at the rear of the U-shaped pieces 29, which conductors 33 are formed into a cable 34 similar to cable 24, which cable 34 extends to the external electrical circuits. It will be noticed in Fig. 2 that the prong 9 in the left hand upper corner of the male portion of the present plug coupling means is turned 90° with respect to the other prongs 9, and likewise the socket corresponding thereto in the female portion is also turned 90° with respect to the other sockets, and it may be seen in Fig. 1 that this arrangement is duplicated on each side. In other words, it may be seen in Fig. 1 that the sockets in each of the lower corners of the figure are turned 90° relative to the other sockets, and the prongs of the male portion being similarly arranged, it will be clear that the male and female portions can only be coupled together in one position which insures that conductors 33 are properly connected to the associated conductors 23.

In order to retain the 2 portions in their coupled position against jars or vibrations which might tend to cause their separation, a spring hasp 38 is provided. This hasp 38 is formed of a strip of spring metal such as phosphor-bronze having a wide portion retained between grooves formed in webs molded into the upper part of the cover 14 of the male portion with a T-shaped end preventing its withdrawal from this groove in one direction. In installing the hasp 38, a narrower portion thereof can be placed downwardly between the webs of the cover 14 having the retaining grooves and the hasp then pulled forward so that the wide portion enters these grooves. A center portion 39 cut out on three sides and sprung downwardly is permitted to snap down to a position engaging the edge of the cover 14 when the hasp 38 is installed in this manner thus retaining the hasp in its illustrated position.

The extending end of the hasp 38 is bowed upwardly so that when the male and female members are in their coupled position, a downward pressure on the end of hasp 38 is effective to extend the end to a position allowing its T-shaped outer end to hook over the rear edges of the webs in cover 14 of the female portion thus retaining the plug coupling members in the assembled position. It will be clear that as the covers 14 of the male and female positions are identical the hasp 38 may be carried by either the male or female member. In Fig. 2 it may be seen that the panel 8 of the male portion is provided with a slightly extending outer rim which fits into a depressed edge around the panel 28 of the female portion, thus forming a slightly overlapping joint which prevents the accumulation of dust or dirt between the panels which might interfere with the proper coupling of the two members.

A detachable plug connecting means for electrical devices has thus been provided having a detachable member to which the external conductors are permanently connected which can be plug-coupled to an associated member carried by the electrical device and to which the elements of the electrical devices are permanently connected whereby to permit the electrical device to be removed from an electrical system and replacement

made in a minimum length of time. In the present plug coupling means, prongs have been provided having a rectangular cross section which enter sockets formed by resilient contact strips bowed inwardly to provide wiping contacts with both sides of the prongs, and these contacting strips are provided with reinforcing members of non-resilient material which bear against the walls of the retaining panel to insure proper contacting pressure. The resiliency of the bowed contacting strips on each side of the prongs in this arrangement insures that a good electrical contact will be made regardless of slight differences which might occur in manufacture between the spacing of the prongs and the spacing of the sockets.

Another important feature of the present plug coupling device is the removable cover which is provided on each of the separable members, which cover is removed in attaching the electrical conductors to the prongs and sockets thus enabling such connections to be conveniently made, and when the cover is replaced, these connections are protected from damage and the contacts are completely enclosed to guard against short circuits or damage. A simple and reliable means has been provided preventing the separable members of the plug coupling means from being improperly connected by employing prongs having rectangular cross sections with certain prongs turned about their longitudinal axis to positions permitting the coupling together of only the associated electrical circuits.

The above rather specific description of one form of the present invention is given solely by the way of example, and is not intended, in any manner whatsoever, in a limiting sense. It will be obvious that the general principles herein disclosed may be embodied in other organizations different from those illustrated without departing from the spirit or scope of the invention except as limited in the following claims.

What I claim is:

1. In a plug connector, in combination, a support member, a rectangular compartment therein, a receiving socket in the member compartment for receiving a flat prong, the socket including a rigid U-shaped outer strip formed from a single flat strip of material and having an elongated pressed together finger extending from the base of the

U, a shouldered aperture at one end of the compartment receiving the finger with the base of the U bearing against the shoulders, a resilient U-shaped contact member formed from a single piece of material and positioned in the outer strip with a pressed together finger held in the outer strip finger and with each leg of the contact member bowed inwardly toward the other and shoulder means at the other end of the compartment against which the free ends of the contact member legs bear for cooperating with the apertured shoulders to hold each leg so that each of its ends always bears at a fixed position against a leg of the outer strip.

2. In a plug connector, in combination, a first member, a prong extending from the member, a second member, a receiving socket in the second member for receiving the prong, the prong being flat, and the socket including a rigid U-shaped outer strip formed from a single strip of material and having an elongated pressed together finger extending from the base of the U, a resilient U-shaped contact member formed from a single piece of material and positioned in the outer strip with a pressed together finger held in the liner finger and with each leg of the contact member bowed inwardly toward the other, means holding the legs so that each leg has each of its ends always bearing at a fixed position against a leg of the outer strip, and a longitudinally elongated inwardly pressed out portion in each of the contact member legs.

3. In a plug connector, in combination, a support member, a receiving socket in the member for receiving a flat prong, the socket including a rigid U-shaped outer strip formed from a single strip of material and having an elongated pressed together finger extending from the base of the U, a resilient U-shaped contact member formed from a single piece of material and positioned in the outer strip with a pressed together finger held in the outer strip finger and with each leg of the contact member bowed inwardly toward the other and means on the support member for holding the legs so that each leg has each of its ends always bearing at a fixed position against a leg of the outer strip, and a longitudinally elongated inwardly pressed out portion in each of the contact member legs.

OSCAR S. FIELD.
